UNITED STATES PATENT OFFICE.

ERNEST H. BAXTER, OF CHICAGO, ILLINOIS.

FUSE-PLUG.

1,384,028.

Specification of Letters Patent.

Patented July 5, 1921.

Application filed August 5, 1916. Serial No. 113,289.

(GRANTED UNDER THE PROVISIONS OF THE ACT OF MARCH 3, 1921, 41 STAT. L., 1313.)

To all whom it may concern:

Be it known that I, ERNEST H. BAXTER, a citizen of the United States, residing at Chicago, in the county of Cook and State 5 of Illinois, have invented a certain new and useful Improvement in Fuse-Plugs, of which the following is a full, clear, concise, and exact description, reference being had to the accompanying drawings, forming a part 10 of this specification.

My invention relates to fuse plugs, and more particularly to that style of fuse plugs which are called refillable, by which I mean fuse plugs of the character adapted to permit of the ready insertion of a new fuse by a layman should the original fuse be operated or blown. When fuse plugs of this character are refilled by laymen it is necessary that the fuse plug be of such character 15 that it can accommodate only the particular size of fuse wire which will protect the particular circuit upon which the plug is used.

In accordance with my invention I so arrange the fuse plug that a gage is provided which will permit of a fuse of a given capacity being inserted, or one of less capacity, but will prevent the insertion of one of a greater capacity. Means are then provided 20 so that this gage must be used if the fuse is to be inserted at all.

I will explain my invention more in detail by referring to the accompanying drawings, in which—

35 Figure 1 is a top view of my improved fuse structure with the cover plate removed;

Fig. 2 is a bottom view of the same;

Fig. 3 is a sectional view on line *a—a* of Fig. 1 with the cover in place;

40 Fig. 4 is a fragmentary perspective view of the gage structure;

Fig. 5 is a top view of a modified form, and

Fig. 6 is a sectional view thereof on line *b—b* of Fig. 5.

Referring more particularly to Figs. 1, 2, 3 and 4, I show a fuse plug having the base or body portion 1 on which is secured the central contact 2 and the outer screw 50 threaded contact 3, which as customary make contacts with the two contacts provided in the ordinary socket. The screw threaded contact 3 is connected to my improved gage structure 4, which consists of the down-

wardly extending arm 5, the horizontal portion 6 and the vertical portion 7 which forms the gage and guard. A screw 8 is adapted to hold the gage structure in position as is readily apparent. The plate 7 has a hole 9 which forms the gage proper. The screw 60 2 likewise holds a gage plate 10 in position having the hole 11. These holes 9 and 11 are of such size as to accommodate a fuse wire 12 of the proper size to protect the particular circuit for which the plug is rated. 65 Of course, a fuse of smaller capacity could be inserted, but not a fuse of larger capacity. The fuse is then inserted by having one extremity fastened under the screw 2, the free end then inserted through the hole 11 70 so that the fuse stands upwardly, whereupon the free extremity is then inserted through the hole 9 and the extreme extremity held under the screw 8. A cap plate 13 then incloses the fuse, this cap plate being 75 provided with the customary transparent window 14. The gage plate 7, it will be seen, fills the entire space across the interior of the fuse structure thus making it impossible to connect a fuse to the screw 8 80 unless this fuse passes through the hole 9. This gage plate 7 also extends upwardly as more apparent from Fig. 3 so that it is flush with the upper surface of the plug and thus extends directly into contact with 85 the window 14. The device as thus constructed permits the insertion or connection between the terminals 2 and 8 of a fuse only of the right capacity or of a less capacity.

Referring more particularly to Figs. 5 90 and 6, I show a modified form of my invention in which the base structure 1^a has a bridge 15 which connects directly with the outer contact 3. The central contact 2^a is split and has a nut 16 which when screwed down into the position shown in Fig. 6 95 brings the split ends of the outer contact 2^a together, thus to hold the fuse 12 securely in position. The inner extremity of this outer contact 2^a again has the gage hole 11. 100 The upper extremity of the bridge 15 likewise is split at its extreme extremity, these extremities being forced together by the wing nut 17 when the fuse is in place. The lower portion of this bridge again has the 105 gage hole 9 to permit only of the insertion of the right size fuse as already explained. It is of course apparent that instead of a

round fuse a flat fuse can be used or fuse of any other shape so long as the gage is made accordingly. It will be noted that the screw 2 is large enough to cover the gage 5 hole 11 so that none of the melted fuse can escape into the socket to short circuit the terminals thereof.

Having thus described two forms which my invention may take, what I claim as new 10 and desire to secure by Letters Patent is:

1. A refillable fuse plug of the character described having two connecting terminals each adapted to receive and secure the free 15 end of a fuse adapted to extend from one connecting means to the other, and a gage plate mounted within said fuse plug, said gage plate having a hole therethrough to accommodate a predetermined size of fuse, 20 said gage plate extending across the path of the fuse to prevent access to one of said connecting means except through said hole.
2. A refillable fuse plug of the character described having two connecting terminals each adapted to receive and secure the free 25 end of a fuse adapted to extend from one connecting means to the other, and means mounted within said fuse plug, said means including a gage plate having a hole to accommodate a predetermined size of fuse, 30 said means preventing the interposition of a

fuse between said connecting means except through said gage hole aforesaid.

3. A refillable fuse plug of the character described having two connecting terminals each adapted to receive and secure the free 35 end of a fuse adapted to extend from one connecting means to the other, and a gage plate mounted within said fuse plug, said gage plate having a hole therethrough to accommodate a predetermined size of fuse, 40 said gage plate extending across the path of the fuse to prevent access to one of said connecting means.

4. A refillable fuse plug of the character described having two connecting terminals each adapted to receive and secure a free end 45 of a fuse adapted to extend from one connecting means to the other, and means having a gage hole entirely screening one connecting means to prevent the interposition of a fuse between said connecting means except through said gage hole.

In witness whereof I hereunto subscribe 50 my name this 27th day of July, A. D. 1916.

ERNEST H. BAXTER.
